INCLINED THREAD EYE FOR LOOM SHUTTLES

Filed May 3, 1939

UNITED STATES PATENT OFFICE

2,226,266

INCLINED THREAD EYE FOR LOOM
SHUTTLES

Richard G. Turner, Worcester, Mass., assignor to
Crompton & Knowles Loom Works, Worcester,
Mass., a corporation of Massachusetts

Application May 3, 1939, Serial No. 271,545

1 Claim. (Cl. 139—214)

This invention relates to improvements in loom shuttles and it is the general object of the invention to provide a shuttle having the advantages of a pull-back tension and a low delivery eye at the point where the thread leaves the shuttle.

5 Pull-back shuttle tensions customarily employ a pivoted wire provided with several thread receiving loops together with fixed pins located between the loops when the pivoted wire swings toward the pins. The axis of the bobbin is ordinarily located approximately one-half way between the top and bottom of the shuttle, and this requires that the thread must enter some part of the shuttle eye which is close to the axis of the 10 bobbin to insure even unwinding. The first loop of the pivoted wire is therefore placed approximately half way between the top and the bottom of the shuttle, but as heretofore made the wire has been substantially horizontal so that the outermost loop is at the same level as the loop first 15 engaging the weft, or in other words, the outer loop is also close to the axis of the bobbin. By this former construction the delivery eye of the shuttle is midway up the front wall.

20 In the weaving of certain types of yarn it is desirable to prevent the thread from being pinched between the binder and the front wall but with the relatively high delivery eye it is necessary to use a rather narrow binder which engages the top half only of the shuttle wall. With 25 the shuttle checking problems incident to high speeds it is desirable to increase the checking area without pinching the filling between the binder and the shuttle. It is a further object of my present invention to provide a shuttle with an inclined pull-back tension wire together with vertical delivery eye posts toward which the thread is led from the inclined tension and from which the thread extends toward the cloth. The range of movements of the swinging pull-back tension 30 are limited to a zone which lies between the top and bottom of the guide posts and the thread therefore always engages some part of the post which is smooth and at a sufficient distance from the adjacent body of the shuttle to prevent entanglement and breaking.

35 Certain features of the shuttle eye to be described hereinafter are similar to those set forth in my co-pending application Serial No. 185,936.

40 With these and other objects in view which will appear as the description proceeds, my invention resides in the combination and arrangement of parts hereinafter described and set forth.

45 In the accompanying drawing, wherein a convenient embodiment of my invention is set forth:

Fig. 1 is a plan view of a shuttle box and shuttle made according to my present invention,

Fig. 2 is a front elevation of part of Fig. 1,

Fig. 3 is a horizontal section on line 3—3 of Fig. 2,

Fig. 4 is a vertical section on line 4—4, Fig. 1,

Fig. 5 is a perspective view of the tension unit,

Fig. 6 is a perspective view of one of the pair of thread guards forming part of the delivery eye, and

Fig. 7 is a transverse vertical section on line 10 7—7, Fig. 2.

Referring to the drawing, the loom lay 10 is provided with a shuttle box designated generally at B and having a box back 11 and a binder 12. 15 The shuttle has back and front walls 14 and 15, respectively, to engage the box back and binder, respectively. The latter preferably has the lower inner or rear surface thereof undercut as at 20 to provide a passage for the thread from the outer end of the shuttle shown at the right of Fig. 1 to the left toward the cloth not shown. The thick upper part 21 of the binder has a vertical rear surface 22 to engage and check the shuttle as the latter is boxed.

25 The shuttle comprises a body 30 having a weft compartment 31 in which is located a weft carrier 32 mounted in the present instance on a spindle 33. The details of the mounting may be varied but should be such as to keep the axis of 30 the weft carrier substantially horizontal when the shuttle is weaving and preferably in line with the axis of the shuttle. The weft W on the carrier may be wound so as to have a conical end 35 facing the eye end of the shuttle and from which the 35 thread is unwrapped as it is drawn to the left as viewed in Fig. 1. During the unwinding the thread passes around the tip 36 of the carrier in the usual manner, and in certain positions is resisted more by the tip 36 than in other positions. 40 That part of the shuttle thus far described may be of common construction and of itself forms no part of my present invention.

45 In carrying my invention into effect I form the shuttle with a tension slot or compartment 40 which extends transversely through the shuttle body. The top and bottom walls 41 and 42, respectively, of the compartment are substantially parallel and are inclined downwardly and toward the adjacent end of the shuttle. Within this slot 50 or compartment I locate a tension unit carrier 45 having top and bottom plates 46 and 47, respectively, and having a comparatively long end wall 48 which fits against the outer lower end 49 of the weft compartment. The inner edge of 55

the carrier 45 is cut away to define a notch 50 at the sides of which are front and back short walls 51 and 52, respectively, which abut corresponding parts of the shuttle body 53. The notch 50 may 5 be formed as indicated in Figs. 3 and 5 by removing a portion of the top and bottom plates. The shuttle body is similarly provided with a notch 55 at the left end of the weft compartment as viewed in Fig. 1. When the unit carrier is in 10 place in the shuttle the notch 50 aligns vertically with the corresponding notch 55 in the shuttle body to define a tapered end of the weft compartment toward which the weft is led as it unwinds.

15 A pin 60 extends between and is secured to the top and bottom plates 46 and 47 of the unit carrier and has pivoted thereon a swinging tension member 61 formed preferably of wire and having a bearing 62 to surround the pin 60 and 20 from which projects a finger hold 63. In the present instance I form the tension member with three eyes or loops 65, 66 and 67, respectively. In order to hold the unit carrier in the shuttle I provide the top and bottom plates there- 25 of with holes 69 one of which is shown for instance at Fig. 5 and pass through these holes a retaining screw 70 which may be somewhat inclined as indicated in Fig. 4. This screw passes through the unit carrier into the lower part of 30 the shuttle body and serves to prevent movement of the carrier 45 in a transverse direction in slot 40. An elastic 72 has one end thereof secured to the screw 70 and the other end is attached as at 73 to the outer end of the tension- 35 member 61. By turning the screw 70 the tension of the elastic 72 can be altered. The normal effect of the elastic is to hold the unit 61 in the dotted position indicated in Fig. 1 with the axes of the eyes 65, 66 and 67 substantially parallel to 40 the axis of the shuttle. This last relationship is not essential but I have found it convenient.

Extending between and secured to the top and bottom plates 46 and 47 are a pair of spaced tension pins 75 and 76 which are so located as to 45 lie between the eyes or loops on the tension member 61 when the latter is swung from its normal position in a counter-clockwise direction around its pivot 60 to some such position as indicated in Fig. 3. These pins 75 and 76 are fixed and 50 cooperate with the eyes on the tension unit 61 to take up or tension the weft when the elastic 72 retracts the tension member 61 to the position shown in dotted lines in Fig. 1.

The thread is delivered from the shuttle be- 55 tween a pair of spaced eye pins 80 and 81 which are secured vertically in the shuttle as indicated in Fig. 2. These pins cross the tension unit com- 60 partment 40 and have alternate engagement with the weft as the shuttle moves from one side to the other of the loom during the weaving opera- 65 tion.

In order to prevent the thread from being 65 caught between the shuttle body and the ends of the eye pins 80 and 81 I may provide guards 85 as indicated in Fig. 6. Each guard will have a tapered end 86 and a curved vertical wall 87. The bottom and top plates are recessed as at 88 for the accommodation of the guards 85 and the height of the wall 87 is equal to the vertical dis- 70 tance between the top and bottom walls of the tension unit compartment 40. As indicated in Fig. 2 each of the eye pins 80 and 81 has a curved wall 87 extended partly therearound and the tapered ends 86 are so disposed that their adja- 75 cent edges 90 are substantially horizontal. By

this arrangement the delivery eye designated at E in Fig. 3 is defined by the vertical posts 80 and 81 and the horizontal edges 90, thereby providing a thread delivery eye of substantially rectangular form as shown in Fig. 2. 5

In operation, the swinging member 61 is normally in the dotted position of Fig. 1, but will be moved manually against the action of the elastic 72 by means of finger hold 63 so that the straight portion 95 thereof will lie against the pins 75 and 76. A threading hook of common construction is then passed through the delivery eye E and the aligned eyes 67, 66 and 65 into the weft compartment 31 to receive the weft W, after which the hook is pulled back out of the delivery eye E, thereby threading the tension unit and delivery eye. When released the swinging member moves to normal position, the screw 70 acting as a stop to limit angular motion of the member 61 in a clockwise direction as viewed in Fig. 1. The thread is then disposed in zigzag form by the loops and fixed tension pins as shown in Fig. 1. 15

During weaving the tension on the weft will move the member 61 toward the fixed pins 75 and 76, thereby shortening the path of the weft through the tension unit. When the shuttle comes to rest excess weft is taken up by movement of the member 61 away from the fixed pins 75 and 76. 25

As previously stated, it is desirable that the thread move toward the tension unit along a line closely paralleling and preferably coincident with the axis of the shuttle, and this relationship requires that the first loop 65 to be entered by the weft shall be approximately half way between the top and bottom of the shuttle, or in line with the shuttle and bobbin axes. During the passage of the weft through the tension unit 61, however, it has a generally downward direction so that it emerges from the last loop 67 in a position lower than that which it had when entering the first loop 65. The delivery eye E can therefore be located comparatively low in the shuttle with assurance that the thread will lie below the surface 22 of the binder and the latter can be made substantially wider than half the height of the front shuttle wall. The fact that the eye posts 80 and 81 are vertical insures maintenance of a horizontal position of the weft as the latter leaves the shuttle and moves toward the cloth without tendency for the thread to creep up or down on the posts. 30

The pivot pin 60 is perpendicular to the plates 46 and 47 and therefore inclined, with the result 35 that the loop 67 has a slight rise and fall as member 61 swings. The range of this vertical motion, however, is limited and keeps the thread usually in contact with the intermediate parts of the posts 80 and 81. I do not wish to be limited to the inclined pivot 60, however, since the advantages of my invention are not dependent upon the position of pivot 60 as shown herein. 40

From the foregoing it will be seen that I have provided a shuttle including a pivoted multi-looped member which swings in a plane inclined 45 downwardly and toward the adjacent end of the shuttle for the purpose of delivering the weft thread at a point lower than that at which it is received by the swinging member. The resultant 50 lowered position of the delivery eye makes it possible to use a binder having a relatively wide shuttle engaging surface 22. It will also be seen that the posts 80 and 81 are vertical for the purpose of maintaining the weft in a substantially 55 60 65 70 75 80 85 90 95 100

horizontal position without tendency to creep toward the top or bottom of the posts. Furthermore, the guard arms 86 prevent the weft from having direct contact with the body of the shuttle.

Having thus described my invention it will be seen that changes and modifications may be made therein by those skilled in the art without departing from the spirit and scope of the invention and I do not wish to be limited to the details herein disclosed, but what I claim is:

In a weft shuttle having a bobbin supply with a horizontal axis, a weft tension carrier extending transversely of the shuttle and having spaced top and bottom walls both of which are inclined downwardly and toward the adjacent end of the shuttle, a tension member pivoted to the car-

rier and having spaced thread receiving loops movable between the walls, a tension pin fixed with respect to the carrier and located intermediate the loops, and a delivery eye for the shuttle below said axis, the pivoted tension member 5 swinging in a plane and extending in a direction inclined downwardly toward the adjacent end of the shuttle, the loop of the member adjacent the weft supply being substantially in alignment with the said horizontal axis and receiving the weft 10 directly from the weft supply, and the loop nearest the adjacent end of the shuttle being in a lower position and below said axis, said loops and tension member cooperating to direct the weft in a downwardly inclined sinuous path from the axis 15 toward said delivery eye.

RICHARD G. TURNER.
